OSCILLATING FLOW COMBUSTION CHAMBER

Arthur W. Blackman, Jr., Manchester, and Arthur E. Wetherbee, Jr., Newington, Conn., assignors to United Aircraft Corporation, East Hartford, Conn., a corporation of Delaware

Application February 14, 1956, Serial No. 565,396

5 Claims. (Cl. 60—39.69)

This invention relates to combustion chambers and more particularly to combustion chambers having oscillating flow and combustion characteristics.

It is known that highly efficient burning is attained in combustion chambers when the phenomenon known as screech or oscillating flow occurs. However, with this burning characteristic the oscillations are normally uncontrollable to the extent that in an extremely short time they may become sufficiently violent to damage or destroy the particular combustion chamber. This burning characteristic occurs in afterburners of turbine type power plants, ramjets, or similar power plants where high temperatures and high burning rates are encountered. This type of combustion usually occurs in high output combustion chambers and is characterized by high amplitude oscillations occurring at a resonant frequency of the combustion chamber cavity. When this type of combustion is encountered the heat transfer rate to the combustion chamber wall is increased greatly. This increased heat transfer rate coupled with the high stress repetition rates of the pressure oscillations cause rapid failure of the combustion chamber structural components.

It is therefore an object of this invention to obtain the advantages of this type of combustion but to eliminate structural failures by controlling the amplitude of the pressure oscillations.

It is a further object of this invention to increase the fluid mixing associated with oscillatory combustion and to increase the heat release rates in the process of the combustion reactions by providing a means for completing combustion in a much shorter combustion chamber length for a given efficiency level.

These and other objects of this invention will become readily apparent from the following detailed description of the drawing in which:

Fig. 1 is a schematic sectional illustration of a combustion chamber of rectangular cross section constructed according to this invention.

Fig. 2 is a cross-sectional illustration taken along the line 2—2 of Fig. 1.

Fig. 3 is similar to Fig. 1 but illustrates a combustion chamber having a circular cross section, and

Fig. 4 is a cross-sectional illustration taken along the line 4—4 of Fig. 3.

Screeching combustion can be used practically if the amplitude of the pressure pulsations are controlled by properly locating the flamefronts with respect to the combustion chamber walls and by providing a properly designed absorption liner in the combustion chamber. Although the type of oscillatory combustion can be further controlled by regulating the fuel air limits, it is the provision of an absorptive liner of proper characteristics which can best provide highly efficient yet safe combustion.

It is known that the pressure oscillations during screech or oscillatory combustion can be either acting along the

2

axis of flow through the combustion chamber or transversely thereof. It has been found that the transverse oscillations produce more efficient burning and can be produced and controlled in accordance with the teachings of this invention.

Referring to Fig. 1, a combustion chamber is generally indicated at 10 including a plurality of fuel nozzles 12. A V type flameholder 14 with suitable means of ignition 15 is provided with its downstream end terminating in a lip 16 radially spaced outwardly from the axis of the combustion chamber. The ignition means 15 may be a pilot flame as shown or any other suitable form such as electrical or pyrotechnic ignition. By properly locating the lip 16 from the axis of the combustion chamber the preferred frequency of transverse oscillations during combustion can be obtained. In addition an absorptive liner 20 is provided between the lip 16 and the outer wall 22 of the combustion chamber. The spacing of these components is related to other dimensions of the combustion chamber as described hereinafter. It should be noted that the perforations in the liner 20 comprise radially extending unobstructed passages to permit free radial flow of pressure fluctuations.

Fig. 1 illustrates a rectangular combustion chamber the relative shape and dimensions of which are more clearly shown in Fig. 2.

Fig. 3 illustrates a circular combustion chamber generally indicated at 30 as having fuel nozzles 32 and a conical flame-holder 34 which terminates in a downstream lip 36. The downstream lip 36 is spaced radially from the axis of the flow through the combustion chamber and this spacing is related to other dimensions of the combustion chamber as described hereinafter. An annular absorptive liner 40 is provided, and this liner is spaced inwardly from the outer combustion chamber casting 42 but is spaced radially outwardly from the lip 36 of the flameholder. The particular configuration of the circular combustion chamber is better illustrated in Fig. 4.

The particular size and shape of the elements of this invention necessary to produce the proper oscillatory combustion with the best efficiency is set forth hereinafter. Thus for example a transverse mode of oscillation can be excited more easily than a longitudinal mode of oscillation if the length to diameter ratio of the combustion chamber is less than or equal to approximately 4 (see dimensions on Figs. 1 and 3). When the particular size of the combustion chamber for any particular requirement is determined, it is possible to then define the location of the flamefront (outer lip of the flameholder) and the type of absorptive liner in terms of one or more dimensions of the combustion chamber.

According to this invention, then, it is best to excite the lowest frequency of a transverse mode of oscillation. This frequency may be expressed as:

$$f = \frac{1.84C}{D} \text{ for cylindrical duct}$$

$$f = \frac{C}{2h} \text{ for a rectangular duct}$$

where

60 f =frequency

C =speed of sound

D =liner diameter

65 h =longer side of rectangular duct

Since the absorption liner of this invention will be tuned to the frequency generated or excited in the combustion chamber, its properties are also related to the

frequency (f). Therefore it can be further shown that the liner qualities or design parameter ϕ is given as

$$\phi = \frac{\sigma}{L_{\text{eff}}} = \frac{13.55}{D^2} \text{ for cylindrical combustion chamber}$$

and

$$\phi = \frac{\sigma}{L_{\text{eff}}} = \frac{\pi^2}{h^2} \text{ for rectangular combustion chambers}$$

where

$$\sigma = \text{percent open area of absorber}$$

$$L = \text{air depth behind absorber facing}$$

$$L_{\text{eff}} = \text{effective length of air column in liner perforations}$$

$$L_{\text{eff}} = [t + 1.7\gamma_0(1 - 0.75\sigma)]$$

$$t = \text{liner face thickness}$$

$$\gamma_0 = \text{radius of each liner perforation}$$

Hence once the diameter of the combustion chamber is established (in the case of a cylindrical configuration) a liner with the proper design properties can be selected. Thus knowing that design parameter ϕ is equal to $13.55/D^2$, which in turn is identical with the variables shown above which comprise ϕ , it is possible to design or choose the correct type of liner. The same holds true for a rectangular combustion chamber.

It has been found that for efficient operation the distance of the flameholder lip from the longitudinal axis of the combustion chamber in the case of a cylindrical section is approximately equal to a value of 0.35 to 0.40 of the diameter of the absorptive liner. On the other hand the desirable distance of the flameholder lip from the longitudinal axis in the case of a rectangular section is approximately equal to or greater than a value of 0.35 to 0.40 of the dimension of the side of the rectangle formed by the duct.

It is readily apparent then that as a result of this invention controlled oscillations can be produced in combustion chambers to reduce space requirements while at the same time avoiding destructive, high amplitude pressure oscillations.

The term combustion chamber so used herein is intended to include without limitation, reaction chambers where chemical reactions, decompositions or other similar process may occur since this invention is equally applicable thereto.

Although only two embodiments of this invention have been illustrated and described herein, it will become readily apparent that various changes and modifications may be made in the construction and arrangement of the various parts without departing from the scope of this novel concept.

We claim:

1. In a combustion chamber, a cylindrical outer casing for defining a cylindrical burner duct, said duct having a longitudinal axis, a perforated cylindrical liner coaxially disposed in said duct, said liner with said duct forming a tuned chamber open at both ends, the perforations of said liner comprising radially extending unobstructed passages, a conical flameholder in said duct and having an outer lip located adjacent said liner, said lip being spaced from said axis a distance which is greater than 0.35 to 0.40 of the diameter of said liner, and means for introducing fuel upstream of said flameholder.

2. In a combustion chamber, a cylindrical outer casing for defining a cylindrical burner duct, said duct having a longitudinal axis, a perforated cylindrical liner coaxially disposed in said duct, said liner with said duct forming an annular chamber open at both ends for free flow through said chamber, the perforations in said liner comprising radially extending unobstructed passages, a conical flameholder in said duct and having an outer lip located adjacent said liner, said lip being spaced from said axis a distance which is greater than 0.35 to 0.40 of the diameter of said liner, the distance from said lip to the

downstream end of said combustion chamber being approximately equal to a distance less than four times the diameter of said liner, and means for introducing fuel upstream of said flameholder.

3. In a combustion chamber, a tubular outer casing for defining a cylindrical burner duct, said duct having a longitudinal axis, a perforated cylindrical liner coaxially disposed in said duct, said liner with said duct forming an annular tuned chamber open at both ends along said axis, the perforations in said liner comprising unobstructed passages running normal to said axis, a flameholder in said duct having a V cross section and having its downstream end terminating in an outer lip radially displaced from said axis and adjacent said liner, said lip being spaced from said axis approximately equal to a distance which is of a value approximately in the range of 0.35 to 0.40 of the diameter of said liner.

4. A combustion chamber having a casing for defining a burner duct, said duct having a longitudinal axis, means for injecting fuel at an upstream station in said duct, imperforate flameholder means in said duct downstream of said fuel injecting means, and terminating in at least one outer lip from which a flamefront emanates in a downstream direction, said lip being located a distance away from said axis, and an absorptive liner coaxially disposed with respect to said casing and being radially located between said lip and said casing thereby forming a space therebetween, said liner being cylindrical and perforated substantially throughout its length, said perforations comprising unobstructed radial passages extending substantially normal to said axis, the upstream end of said liner being located adjacent said lip and extending downstream thereof whereby said liner lies substantially in the flamefront and whereby said space forms a tuned chamber open at its axial ends.

5. A combustion chamber having a casing for defining a burner duct, said duct having a longitudinal axis, means for injecting fuel at an upstream station in said duct, imperforate flameholder means in said duct downstream of said fuel injecting means, and terminating in at least one outer lip from which a flamefront emanates in a downstream direction, said lip being located a distance away from said axis, and an absorptive liner coaxially disposed with respect to said casing and being radially located between said lip and said casing thereby forming a space therebetween, said liner being cylindrical and perforated substantially throughout its length, said perforations comprising unobstructed radial passages extending substantially normal to said axis, the upstream end of said liner being located adjacent said lip and extending downstream thereof whereby said liner lies substantially in the flamefront and whereby said space forms a tuned chamber open at its axial ends, said lip being spaced from said axis a distance which is .035 to .045 of the maximum cross-sectional dimension of said liner, the distance from said lip to the downstream end of said combustion chamber being approximately equal to a distance less than four times the said maximum cross-sectional dimension of said liner.
